Primary Examiner—Freda Nunn
Attorney, Agent, or Firm—Francois Martineau**[57]****CLAIM**

The ornamental design for a personal computer keyboard assembly, as shown and described.

DESCRIPTION

FIG. 1 is a top plan view of the personal computer keyboard assembly showing my new design;

FIG. 2 is a front elevation thereof;

FIG. 3 is a rear elevation thereof;

FIG. 4 is a bottom plan view thereof;

FIG. 5 is a left-hand side view thereof; and,

FIG. 6 is a right-hand side view thereof.

The cords are shown broken away in the views to indicate an indeterminate length.
